UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

TYPGRAPHICAL MACHINE.

1,126,481.

Specification of Letters Patent.

Patented Jan. 26, 1915.

Application filed September 19, 1914. Serial No. 862,428.

To all whom it may concern:

Be it known that I, GEORGE P. KINGSBURY, a citizen of the United States, residing at Brooklyn, in the county of Kings and State of New York, have invented certain new and useful Improvements in Typographical Machines, of which the following is a specification, reference being had thereto in the accompanying drawing.

10 My invention relates to typographical machines, such as linotype machines of the general organization represented in Letters Patent of the United States, No. 436,532, to O. Mergenthaler, wherein circulating matrices are released from a magazine or magazines in the order in which their characters are to appear in print and then assembled in line, the composed line transferred to the face of a mold, the mold filled with molten 20 metal to form a slug or linotype against the matrices which produce the type characters thereon, and the matrices thereafter raised by the second elevator and delivered to the distributing mechanism from which 25 they pass to the magazine from which they started.

More particularly, it relates to means whereby the abnormal operation of the second elevator, such as its arrest in its uppermost position, effects the immediate stoppage of the machine. The purposes and advantages of this arrangement will hereafter more fully appear from the detail description thereof.

30 In the accompanying drawings, I have shown my invention in preferred form and by way of example, and as applied to a linotype machine, but many changes and variations may be made therein, and in its mode of application, which will still be comprised within its spirit. Generally speaking, I desire it to be understood that I do not limit myself to any specific form or embodiment, except in so far as such limitations are specified in the claims.

Referring to the drawings: Figure 1 is a rear skeleton elevation of certain parts of a linotype machine embodying my invention; Fig. 2 is a sectional detail of the elevator cam, stop device, etc.; and Fig. 3 is a plan thereof, partly in section.

As illustrated in the Mergenthaler patent previously referred to, or as is customary in the somewhat modified commercial linotype machine, after the slug is cast, and the

first elevator rises to its uppermost position, the line of matrices and spacers is transferred therefrom by the slide G into the upper transfer channel (not shown), where the matrices engage with the second elevator 60 bar A. The bar A is carried by the arm B provided with an arm and roller C located in suitable position to be engaged and actuated by the cam D, whereby the bar is moved upwardly into registration with the distributor box A¹, to which the matrices are shifted in the ordinary way by the slide A². The spacer hook (shown by dotted lines in Fig. 1) is operatively connected to the slide G, in such manner that when the slide moves 70 the line into the transfer channel, the hook advances and engages the spacers remaining therein, and by its return movement restores them to the spacer magazine. The slide G is held in its retracted or inoperative position by the pivoted pawl or detent J. In normal operation, the detent is tripped to release the slide by the contact therewith of an abutment B² connected to the elevator arm B, in such manner that when the latter 80 descends into operative relation to the intermediate channel, the slide is permitted to operate. The parts so far described are or may be of any usual or preferred construction, and except as hereinafter specified, constitute no part of my present invention.

The means for actuating the slide G and the spacer hook are somewhat similar to those presented in Letters Patent of the 90 United States to O. Mergenthaler, No. 557,000. The slide G is operated by the intermediate link G¹ connected to an upright arm G², and the spacer hook is carried by the upright G³, these parts being connected 95 in the well-known manner. The arms G² and G³, and consequently the slide G and spacer hook, are operatively moved by the powerful spring G⁴, and are returned to normal position by the action of the cam H 100 upon the arm G⁵, all in the ordinary way. The cam is so formed that when the spring G⁴ acts to shift the slide G inwardly, its movement is controlled and uniform, which is necessary to secure the proper transfer of 105 the matrices to the elevator bar A, as a sudden or jerky action would project them violently and spill them into the machine.

It sometimes happens in use that the elevator bar A is prevented from descending at 110

the proper time, as for instance when due to the arrest of the distributor, the matrices are not properly transferred to the distributor box and a jam occurs which holds the elevator in its uppermost position. When this happens, it is ordinarily necessary for the operator to leave his place at the keyboard and pass to the rear of the machine, in order to correct the difficulty and clear the parts.

10 At this time, the slide G is held in its outward or inoperative position against the force of the spring G¹ by the detent J, although the cam H has continued to move and has passed out of contact with the arm

15 G². When now the second elevator is freed and permitted to descend, it trips the detent J and releases the slide G, which shoots forward with great rapidity, because it is no longer under the control of the cam, and

20 projects the line in front of it with excessive violence and frequently with disastrous results. This condition subjects the operator to great inconvenience, and chiefly because it has been difficult in actual practice 25 to control the slide simultaneously with the clearing and lowering of the second elevator. Various efforts have been made to obviate the objection, such, for instance as the provision of manually controllable devices at

30 the rear of the machine, the provision of a yielding abutment for the slide detent, and the like. In the present instance, I have provided means whereby the abnormal operation of the elevator, such as the arrest of 35 its descent, instantly effects the stoppage of the machine, and thus the continued movement of the cams will be prevented when the elevator is arrested.

40 The elevator cam D and transfer cam H are both mounted upon the cam shaft E, which is actuated through gearing E¹ and E² from the power shaft F. Upon the end of the shaft F is loosely mounted the drum O to which power may be imparted in any 45 suitable manner. Rigidly connected to the end of the shaft F and within the drum O, are the radially movable clutch members P, which in their extended position engage the drum and effect the rotation of the shaft F, 50 and when retracted break the actuating engagement. Pivots connected to the clutch members P and to the end of the bolt Q, mounted in a suitable bore in the end of the shaft F, are the links P¹, the arrangement 55 being such that when the bolt Q is moved inwardly the clutch is closed, and when moved outwardly the clutch is opened. The spring S connected to the bolt tends to give the latter its operative position, at which 60 time the shaft F and the cam shaft E are continuously rotated. The stopping movement of the bolt Q is imparted thereto by the clutch lever M provided at one extremity with the fork N which acts upon the collar 65 R secured to the bolt Q, and at its other ex-

tremity with suitable controlling connections. It will thus be seen that when the lever M is shifted to move the fork N inwardly, the spring S acts to close the clutch, and that when the lever is shifted in the opposite direction against the force of the spring S, the outward movement of the bolt Q acting through the links P¹ opens the clutch. In the arrangement illustrated, I have provided means acting upon the lever 70 M to shift it outwardly and thus arrest the rotation of the cam shaft E, if for any reason the descent of the second elevator be arrested.

75 Referring to Figs. 2 and 3, it will be seen that the elevator arm B and cam arm C are mounted upon the rock shaft B¹; and that also connected thereto is a third arm L provided with a laterally projecting pin L¹ adapted to actuate a stop piece or slide K 80 under certain conditions. The piece K is movably mounted upon the side of the cam H, its arrangement being such that it is permitted to slide thereon to a certain limited extent, and it is provided at one end with a 85 beveled portion K¹ to coöperate with the pin L¹ on the arm L, and at its other end with a depending arm K² to engage a beveled member M¹ on a vertical bracket M² mounted on the clutch lever M.

90 In the normal operation of the parts, as shown by full lines in Fig. 2, the slide K is so located that its beveled portion K¹ will clear the pin L¹ upon the arm L, and its arm K² will clear the beveled member M¹ of the bracket M², this result arising from the continued contact of the arm C with the cam D, when the second elevator is descending in the normal manner. However, if for any 95 reason the descent of the second elevator is arrested, the rotation of the shaft E carries the active surface of the cam D away from and out of contact with the arm C, as shown by dotted lines in Fig. 2, as the latter is held 100 stationary because of its connection to the elevator arm B. In these circumstances the arm L also remains stationary and the pin L¹ stands in the path of the beveled portion K¹ of the slide K, as the latter is rotated by the cam H, the contact of the pin with the bevel acting to move the slide K longitudinally and its arm K² into the path of the beveled member M¹ on the bracket M². The 105 further rotation of the cam H therefore effects, through the action of the arm K² on the bevel M¹, the outward pivotal movement of the clutch lever M, which as before described, results in the opening of the clutch 110 and the stoppage of the machine. The rotary movement of the cam shaft necessary to effect this result is so slight that the stoppage of the machine is practically instantaneous, the cam H having moved through so small an arc, that when the second elevator 115 is cleared and the machine again started,

the action of the spring G^4 upon the slide G and the spacer hook is substantially normal, and therefore the liability to their sudden and violent action is entirely obviated. Moreover, there is no longer necessity for the previously proposed auxiliary safety devices, such as a yielding abutment on the second elevator, or the manually controlled devices at the rear of the machine. It is further pointed out that as soon as the elevator is cleared and the arm C allowed to resume contact with the cam D , the pin L^1 on the arm L will be moved out of the path of the bevel K^1 on the slide K , thus permitting the spring S to act, whereby not only is the clutch again closed, but the slide K is restored to normal position. In other words, the mere clearance of the elevator restores the parts to operative condition without further attention on the part of the operator.

As previously stated, I have shown my invention only in preferred form and by way of example, and as applied to a linotype machine, but obviously many modifications and alterations therein, and in its mode of adaptation, will suggest themselves to those skilled in the art, without departure from its scope.

Having thus described my invention, its construction and mode of operation, what I claim and desire to secure by Letters Patent of the United States, is as follows:

1. In a linotype machine, the combination with the second elevator, of means whereby the abnormal operation of said elevator will instantly effect the stoppage of the machine.
2. In a linotype machine, the combination with the rising and descending second elevator and its operating shaft, of means whereby the arrest of the elevator in its descent instantly effects the stoppage of the machine.
3. In a typographical machine, the combination of a movable line transporter, a cam to control its movement, and automatic means for effecting the stoppage of the machine the instant the operative relation between said parts is disturbed.
4. In a typographical machine, the combination of the second elevator, driving mechanism comprising a clutch, devices for opening the clutch, and means whereby the arrest

of the elevator will effect the actuation of said devices.

5. In a typographical machine, the combination of a movable line transporter, an element connected thereto, machine stop devices, and movable means for actuating said stop devices, the said means being controlled in their movement by their engagement with the element connected to the transporter. 55

6. In a typographical machine, the combination of a movable line transporter, an element connected thereto, driving mechanism comprising a clutch, a rotatable part operated by the driving mechanism, a member 65 carried by the rotatable part and moved relatively thereto by its engagement with the element connected to the transporter, and devices whereby such relative movement of said member will effect the opening of the 70 clutch.

7. In a linotype machine, the combination of the transfer devices normally locked against action, the second elevator adapted to release said transfer devices, a cam to 75 control the movement of said transfer devices when released, and automatic means to effect the instantaneous stoppage of the machine when the elevator is arrested; whereby the cam is prevented from assuming a position where it ceases to control the movement of the transfer devices.

8. In a typographical machine, the combination of a movable line transporter, a receiving part, devices for transferring the 85 line from the transporter to the receiving part, and means whereby the improper transfer of the line by said devices immediately effects the stoppage of the machine.

9. In a linotype machine, the combination 90 with the second elevator and the distributor box to which the line is transferred therefrom, of means whereby the incomplete transfer of the line will instantly effect the stoppage of the machine. 95

In testimony whereof, I have affixed my signature in presence of two witnesses.

GEORGE P. KINGSBURY.
